Primary Examiner—Susan J. Lucas*Attorney, Agent, or Firm*—William Brinks Hofer Gilson & Lione**[57] CLAIM**

The ornamental design for an illuminated rising bubble display, as shown and described.

DESCRIPTION

FIG. 1 is a front right perspective view of an illuminated rising bubble display that incorporates my new design; and,

FIG. 2 is a front view thereof;

FIG. 3 is a right side elevational view thereof;

FIG. 4 is a left side elevational view thereof;

FIG. 5 is a top view thereof; and,

FIG. 6 is a bottom view thereof.

The rear view of my new design is identical to FIG. 2.

FIG. 1

FIG. 2

FIG. 3

FIG. 4

FIG. 5

FIG. 6
